UNITED STATES PATENT OFFICE.

FRED R. SLOCKETT, OF FORT COLLINS, COLORADO.

METALLIC CROSS-TIE.

No. 922,968.

Specification of Letters Patent.

Patented May 25, 1909.

Application filed July 18, 1908. Serial No. 444,198.

To all whom it may concern:

Be it known that I, FRED R. SLOCKETT, a citizen of the United States, residing at Fort Collins, in the county of Larimer and State of Colorado, have invented a new and useful Metallic Cross-Tie, of which the following is a specification.

The invention relates to improvements in metallic cross ties.

10 The object of the present invention is to improve the construction of metallic cross ties, and to provide a simple and comparatively inexpensive one of great strength and durability, adapted to be easily and cheaply manufactured, and capable of advantageous use on all portions of a railroad track.

15 A further object of the invention is to provide a metallic cross tie of this character equipped with rail-engaging means, capable of securely holding the rails and of effectually preventing the same from spreading at curves and other places and dispensing with the use of rail chairs, tie bars and the like.

20 With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

25 In the drawing:—Figure 1 is a plan view of a portion of a track provided with cross ties, constructed in accordance with this invention, a portion of the rails being in section to illustrate the construction more clearly. Fig. 2 is a sectional view, taken substantially on the line 2—2 of Fig. 1. Fig. 3 is a similar view, taken substantially on the line 3—3 of Fig. 1. Fig. 4 is an end elevation, illustrating the arrangement of the 30 clamps and the fastening means. Fig. 5 is a detail perspective view of one of the clamps. Fig. 6 is a detail perspective view, showing another form of the rail clamp. Figs. 7 and 8 are detail sectional views, showing the 35 modified form of clamp applied to a cross tie.

40 Like numerals of reference designate corresponding parts in all the figures of the drawings.

45 The metallic cross tie 1, which may be constructed of any suitable metal, such as steel or iron and which may be manufactured by

any well known method, is approximately U-shaped in cross section being composed of vertical sides 2 and a horizontal connecting bottom portion 3. The horizontal bottom 50 extends entirely across the cross tie, and the tie is angular at the corners formed by the sides and the horizontal bottom. The upper edges of the sides 2 receive and support the rails 3^a, which are secured to the cross tie by 55 means of the clamps 4.

The rail holding clamps, which are constructed of steel or other suitable material, are fitted against the sides of the cross tie and are composed of upper engaging portions 70 or jaws and lower approximately horizontal portions 5, extending across the lower faces of the bottom flanges of the rails and secured to the sides of the cross tie by bolts 6. The jaws or engaging portions of the clamps are 75 reversely arranged to engage the bottom flanges of the rails at the inner and outer sides thereof, and if necessary or desirable, each cross tie may be equipped at each end with either two, three or four clamps. Ordinarily two clamps, as illustrated in the accompanying drawings, will be sufficient, but at portions of the track, where the rails are subjected to increased strain, additional clamps may be used. When the number of 80 clamps is increased, the additional clamps are fitted against the inner faces of the sides of the cross tie, and the bolts 6, which are preferably short, may extend entirely across the cross tie. When short bolts are employed, they pierce the clamps and the sides of the cross tie at points beyond the bottom flanges of the rails, as clearly illustrated in Figs. 2 and 3 of the drawing, and the nuts are preferably located at the inner faces of 85 the sides of the cross tie. The heads of the bolts or screws may be provided with grooves, or polygonal heads may be employed for enabling the bolts or screws to be gripped with a wrench, or other tool, while the nuts are 90 being turned.

In Figs. 6 to 8 inclusive of the drawing, is illustrated a modification of the invention in which the clamp 8 extends entirely across the space between the sides of the cross tie and 105 fits upon and is supported by the horizontal bottom thereof. The clamp 8 is composed of an upper engaging portion or jaw and a lower horizontal portion extending entirely across the lower face of the rail. The clamp 110 8 is secured to the cross tie by means of bolts 9, piercing the clamp and the sides of the

cross tie and having a head at one end and a nut at the other. Instead, however, of arranging the bolt 9 horizontally, as illustrated in Figs. 7 and 8, they may be passed vertically through the clamps and the bottom of the cross tie. This arrangement is especially desirable on bridge work and analogous constructions. At points where the rail joints occur the engaging portions of the clamps 10 are correspondingly shortened, and conform to the configuration of the fish plates where angle fish plates are used.

Having thus fully described my invention, what I claim as new and desire to secure by 15 Letters Patent, is:—

1. The combination with rails, of a metallic cross tie composed of a horizontal bottom portion and vertical sides supporting the rails, rail-engaging clamps arranged exteriorly of the cross tie and including spaced portions or jaws, and lower horizontal portions fitted against the sides of the cross tie and extending across and presenting straight edges to the lower faces of the rails, and short

horizontal bolts piercing the horizontal portions of the clamps and the sides of the cross tie, the nuts of the bolts being located within the cross tie. 25

2. The combination with rails, of a cross tie approximately U-shaped in cross section 30 and provided with vertical sides receiving the rails, rail-engaging clamps fitted against the outer faces of the sides of the cross tie and composed of spaced jaws extending over the bottom flanges of the rails, and lower 35 horizontal portions extending across and projecting beyond the bottom of the rails and presenting straight upper edges to the same, and horizontal bolts piercing the sides of the cross tie and securing the clamp to the same. 40

In testimony, that I claim the foregoing as my own, I have hereto affixed my signature in the presence of two witnesses.

FRED R. SLOCKETT.
